AUDIBLE ELECTRIC SIGNALING APPARATUS

Christian Miller, Norwalk, Conn., assignor to
 Edwards and Company, Inc., Norwalk, Conn., a
 corporation of New York

Application December 31, 1948, Serial No. 68,698

4 Claims. (Cl. 177—7)

1

This invention relates to audible electric signalling mechanisms, and more particularly to electrically actuated bells and buzzers and is a division of my application Serial Number 636,479, matured into Patent No. 2,465,111, of March 22, 1949.

One of the objects of this invention is to provide a compact, strong, durable, and inexpensive construction of the above-mentioned character. Another object is to provide an electrically-actuated audible signalling device that will be of reliable action and well adapted for manufacture and installation. Another object is to provide a device of the above-mentioned character in which the actuating mechanisms will be dependably housed and in which access to the parts necessary for installing or mounting the device may be gained in a simple and facile manner. Another object is to provide a simple, inexpensive, and easily operable means for adjusting the relationship between an electro-magnet and its magnetically-responsive coating parts such as an armature to achieve the desired signalling action of the device. Another object is to carry out the last-mentioned object in a manner to facilitate such adjustment either during manufacture and assembly or after installation of the device. Another object is to provide a signalling device so constructed that it may be readily and easily set for selection of one of several different kinds of audible signals, such as musical or bell-like signals and buzzer-like signals. Another object is to provide a combined bell and buzzer construction in which selection of either bell or buzzer action may be achieved in a simple and dependable manner. Another object is to provide a bell and buzzer construction in which the operating mechanisms are efficiently housed within a bell-shaped or gong-shaped sounding element, yet so constructed that the mechanism may be selectively set for either bell action or buzzer action. Another object is in general to provide an improved bell or buzzer construction, and other objects will be in part obvious or in part pointed out hereinafter.

The invention accordingly consists in the features of construction, combinations of elements, and arrangements of parts as will be exemplified in the structure to be hereinafter described and the scope of the application of which will be indicated in the following claims.

In the accompanying drawing, in which is shown illustratively a preferred form of the various possible embodiments of my invention.

Fig. 1 is a top or plan view, on a small scale,

2

of the complete device as it appears when installed;

Fig. 2 is a top plan view, on a larger scale, showing the device with certain parts, including a frame part, removed so as to show more clearly how the device may be mounted in position and electrical connections made thereto;

Fig. 3 is a top plan view showing the construction with the gong broken away and with a frame part removed;

Fig. 4 is a vertical transverse section as seen along the line 4—4 of Figs. 3 and 1;

Fig. 5 is a bottom plan view as seen from the bottom in Fig. 4, with certain parts broken away;

Fig. 6 is a central vertical sectional view on a larger scale as seen along the line 6—6 of Figs. 3 and 1; and

Fig. 7 is a fragmentary or detached sectional view as seen along the line 7—7 of Fig. 6.

Similar reference characters refer to similar parts throughout the several views of the drawing.

Referring first to Figs. 4, 5 and 6, I provide a frame element 10, which is preferably round where the gong or bell element 11 is round; it is preferably of sheet metal and has a reinforcing side flange 12, the edge of which can rest against the wall or surface to which the device is to be secured, and it is preferably of a diameter greater than that of the gong 11 so as to provide a marginal area, generally indicated at A in Figs. 2 and 3, which is annular while the frame 10 and the gong 11 are circular. Within the marginal area A of the frame 10 are positioned and located certain parts later described in detail and including slot 13 which is given the shape of an inverted T, in the vertical leg portion of which may be accommodated the shank of a securing screw 14 and through the horizontal portion of which (see Fig. 2) the electrical conductors may be passed for connection to the binding posts 15 and 16 in such cases where the wiring is concealed and underlies the frame 10. Diametrically opposed from the slot 13 is a hole 17 in the marginal portion A to receive another fastening device, such as a screw 18 (Figs. 3 and 2).

Underneath the gong element 11 I provide suitable means for supporting it from the frame 10 and also suitable electro-magnetic actuating mechanism, the latter preferably comprising an electro-magnet 19 having a winding 20 and a core 21 (Fig. 6). In the embodiment shown the electro-magnet 19 is preferably positioned considerably to one side of the center and underneath the gong 11, and particularly where it is

desired to achieve greater diminutiveness of construction I am enabled to arrange the core 21 in relation to a magnetic circuit or circuits, making it possible to make winding 20 and hence magnet 19 as a whole, smaller, and in this connection I may employ the gong supporting means and also certain parts uniquely coacting therewith and with the vibratable armature, which is generally indicated by the reference character 22. The supporting means preferably comprises a frame 23, conveniently in the form of a sheet-metal stamping and preferably made of a magnetic material such as iron or steel. It has a horizontal portion that is stepped, principally because of the shape of the gong 11, to provide a part 24 of higher elevation than the other part 25; to the higher part 24 the gong 11 is secured, preferably in a manner to permit the gong to be manually given a rotary movement or displacement. Thus I may employ a screw 26 passing through a central hole in the gong 11 and threaded in the supporting part 24, and where greater permanency of assembly is desired, the screw may fit very tightly into the threaded hole of the part 24 or its shank, after assembly, may be radially expanded or partially headed over to give the effect of a rivet. Such permanency of mounting may be had particularly where, as in the present invention, access to parts underneath the gong, for adjustment or the like, need not be had by removal of the gong, and thus also consistency of musical action of the gong may be better assured. Though the fastening may thus be made substantially permanent, nevertheless it is preferably of such a character as to permit the gong 11 to be manually grasped and turned somewhat about its axis and to be frictionally held in the position to which it is thus turned; this action may be aided by the use of a spring washer 27, which is preferably shaped substantially as shown in Fig. 6 and preferably has a sufficient radial extent to overlie and thus cover an arcuate slot 28 (see also Fig. 2) provided in the top wall of the gong 11 near its center.

The horizontal portion 24-25 of the frame 23 has opposed and preferably parallel, vertical or upstanding arms or parts 30 and 31, or the part 30 is preferably cut out, as at 30^a, to provide transversely spaced end legs 30^b and 30^c (Fig. 4) which are secured to the frame 10 in any suitable way, as by ears 30^d and 30^e which pass through suitable holes in the frame 10 and which are bent over against the underside thereof, as shown in Fig. 5. The opposed vertical part 31 is also shaped to provide transversely spaced legs 31^b and 31^c, which terminate in lugs or ears 31^d and 31^e which pass through holes in the frame 10 and are bent over against the underside thereof. In the case of the part 31, the transversely spaced legs 31^b and 31^c are formed by vertically slitting and bending a substantial portion of the sheet metal outwardly (to the right in Fig. 6) to form a laterally and horizontally projecting bracket 31^a which may, if desired, be stepped, as is better shown in Fig. 6. The bracket 31^a is of substantial width, and hence of substantial cross-section, and it extends into overlapping relation to the annular area A (Fig. 2) of the base frame 10. As is better shown in Fig. 6, the bracket part 31^a may thus extend beyond and underneath the side wall portion 11^a of the gong 11.

Bracket 31^a forms the support or mounting for the armature 22 (Figs. 6 and 5), preferably by

way of a flat leaf spring 32 which is riveted flat-wise against the underside of the bracket 31, as by rivets 33, and has the righthand end of the armature 22 secured thereto, as by rivets 34 (Fig. 6). Where it is desired to have the bracket 31^a form part of the magnetic circuit or circuits of the electro-magnet, I may in this manner, and as is better shown in Fig. 6, bring the right hand end of the armature 22 into close proximity to the bracket 31^a, thus diminishing the magnetic reluctance of the flux paths that make it possible to utilize a very small air gap which, however, is bridged by the flat spring 32 which can be of magnetic material. The bracket 31^a, moreover, provides a mounting for the armature that is considerably displaced to one side of the vertical axis of the gong 11 and thus, by providing the left-hand end of the armature 22 with a striker arm 35 and a gong striker 36 which is juxtaposed to a diametrically opposed portion of the side wall 11^a of the gong 11, I am enabled to give the resiliently or spring-mounted armature and striker structure a very considerable length, thus insuring an efficient whipping action thereof for producing the musical note of the gong when the armature and striker structure are set into vibration by the electro-magnetic mechanism. The striker arm 35 and a striker 36 may be formed integral or in one piece with the armature 22, as by a suitable stamping or punch-press operation.

The right-hand end of the armature 22 thus extends between the rather widely spaced legs 31^b and 31^c of the frame part 31, and the left-hand portion of the structure extends between the spaced legs 30^b and 30^c of the opposed frame part 30, the armature structure lying above the plane of the wall 10^a of the frame 10. The armature 22 is thus held substantially parallel to the horizontal part 25 of the frame 23, and with that arrangement the electro-magnet 19 is mounted, preferably to the part 25, so as to support the core 21 vertically and with its lower end juxtaposed to the armature 22. To mount the electro-magnet, the core 21 may be provided with a reduced end portion 21^a that extends through a hole in the frame part 25 and is headed over as shown, thus forming a good magnetic connection between the core and the frame.

The armature mounting spring 32 has an extension 32^a (Fig. 6) which can be of considerable or appropriate length, due to the structural features of the armature and its mounting as above described, and at its end has a contact element 32^b of a suitable alloy resistive to sparking action. With the mounting spring 32 normally holding the armature 22 spaced from the end of the core 21, the spring contact 32^b engages a contact element 38 (see also Fig. 7) that is carried by part 39^a of a stepped bracket 39 (see Fig. 7), part 39^a being accommodated in some of the space provided by a large rectangular hole 10^b provided in the top wall 10^a of the base 10, whereby the part 39^a may extend below the plane of the wall 10^a; the other part 39^b of the bracket 39 overlies the wall 10^a and is insulated therefrom by two sheets 41 and 42 of insulating material which extends radially outwardly (see Fig. 3) to the periphery of the base frame 10 so they may also serve to insulate the binding post 15 from the frame. Part 39^b (Figs. 7 and 3) is provided with ears 39^c and 39^d by which the frame 39 is clamped to the insulating plates 41, 42, and at the outer end of the latter there is similarly clamped thereto a connector plate 43 by ears 43^a.

and 43^b, connector plate 43 having a threaded hole therein for supporting the binding screw 15 when one of the external circuit wires is connected thereto. Between the two insulating plates 41 and 42 extends a wire 44, which may be bare and which at its end is snaked through the hole through which one of the just-mentioned clamping ears extends, so as to bring the end of the wire underneath the connector plate 43; the other end of the wire 44 can emerge from in between the insulating plates 41—42 at any suitable point, as through a hole in the upper plate 41 (see Figs. 3 and 7) to expose it for making connection to the winding 20. The clamping action of the ears of the parts 43 and 39 thus not only completes the electrical contact with the end of the wire, but also holds all of these parts together as a single unit or entity which may be separately assembled and, as a unit, put into position and assembled to the base 10. The latter is provided with suitable holes 10^c and 10^e (Fig. 5) to accommodate the bent-over ears 39^d and 39^e and thus prevent the latter from contacting the base 10, portions of the sheet metal forming these holes being shaped to provide ears 10^f and 10^g (Fig. 3) which pass upwardly through suitable holes in the insulating sheets 41 and 42 and are bent over to clamp the unit against the upper face of the frame 10. The unit is thus secured adjacent its inner end; at its outer end it is secured by ears 10^h and 10^k formed out of some of the metal that is struck out to form a hole 10^j (Fig. 5) that underlies the ears 43^d and 43^e of the shank of the binding screw 15 so that these parts do not contact the base 10.

With the insulating unit comprising the plates 41—42 thus assembled to the base 10, the pigtail insulated lead wires 20^b—20^a projecting from the electro-magnet 19 may now be soldered respectively to the wire 44 and to the part 39^b (see Figs. 7 and 3) and thus circuit of the winding 20 is completed to the binding screws 15 and 16, through the interrupter formed by the spring part 32^a and the part 39^a of Figs. 7 and 6. More specifically, the circuit may be traced as follows: From insulated binding screw 15, insulated wire 44, pigtail 20^b, winding 20, pigtail 20^a, interrupter contact part 39 and thence to the spring 32^a which is grounded to the frame 23, which is in turn grounded by its mechanical connection to the base 10 in the annular portion A of which (see Figs. 3 and 5) the binding screw 16 is threaded and likewise grounded thereto.

When electrical energy is supplied to this circuit, the electro-magnet 19 is energized to attract the armature 22 upwardly (Fig. 6) and whips the striker 36 upwardly to strike the gong 11 at an appropriate point, which conveniently is a peripheral edge portion of the depending side wall 11^a of the gong 11, the upward movement of the armature 22 interrupting the energization of the winding 20 at the contacts 32^b and 38, whence the spring 32 whips the armature and striker downwardly again to close the energizing circuit at the interrupter contacts, the process being repeated to rapidly vibrate the striker structure for so long as the energizing circuit external to the joining screws 15 and 16 is maintained closed.

As a result, the bell rings; however, it may be preferred to have the device function as a buzzer instead of emitting a musical note, and to convert its action to buzzer action I make provision for permitting the above-described vibrating action of the armature and striker to take place, but without setting the gong 11 into sound-

emitting vibration. A preferred manner of carrying out this provision comprises a controllable change-over device, preferably in the form of a lever, generally indicated by the reference character 46 and better shown in Figs. 4 and 6; it is conveniently in the form of a heavy sheet-metal stamping and may be constructed of steel, particularly where it is desired that it coact in the magnetic circuit of the device, and conveniently is carried by the vertical part 30 of the frame 23, against the upper part of which it rests flatwise and to which it is pivotally connected as by an eyelet 47 that passes through suitable registering holes, and is headed over as indicated in Fig. 6. This pivotal support is preferably close to the upper end of the lever part 46, which has an upward extention 46^a to form a short lever arm that projects above the horizontal part 24 of the frame 23, and is shaped to project into the arcuate slot or hole 28 (see Figs. 2, 4 and 6) provided in the gong 11 and covered over by the spring washer 27 as above described. Accordingly a relatively small rotary movement of the gong 11 about its vertical axis as seen in Fig. 4 is effective, through the driving connection formed by the lever part 46^a and the hole 28 in the gong, to swing the lever 46 about its horizontal axis and give the lower end of the long lever arm 46^b (Fig. 4) a multiplied swing or movement in a plane that intersects the striker arm 35. The lower and longer lever arm 46^b is provided with a horizontal open-ended slot 46^c, preferably tapered or progressively enlarged at its open end (see Fig. 4), the internal portions of the slot 46^c being of a vertical dimension appropriately related to the thickness of the striker 35 and to the stroke of its vibrating movements, as is later described.

Suitable stop means are provided to limit the range of swinging movement of the lever 46, and these may comprise lateral extensions or arms 46^e and 46^f (Fig. 4) bent over at their ends to provide stops 46^g and 46^h adapted for alternate coaction with the side edges of the vertical frame part 30, and they thus also limit the extent of rotary movement which may be manually given to the gong 11.

If the gong 11 is swung in clockwise direction as viewed in Fig. 2, it swings the lever 46 into the position shown in Fig. 4, step 46^g engaging the frame part 30. The frictional resistance provided by the pivotal mounting of the gong 11, and this may be aided by the frictional resistance offered also by the pivotal mounting of the lever arm 46 itself, holds the parts in these respective positions, the lower end of lever 46 being thus held laterally displaced (Fig. 4) from the path of up and down vibrating movement of the striker arm 35 and the latter is free to be rapidly whipped up and down to repeatedly strike the gong 11 and cause it to emit its musical tone.

If, however, the gong 11 is turned in counter-clockwise direction in Fig. 2, the lever 46 is swung in clockwise direction in Fig. 4 to the extent permitted by the engagement of stop 46^h with the frame part 30, and in that position of the change-over lever 46 the striker arm 36, entered through the diverging mouth of the slot 46^c, becomes restricted in its moving strokes during vibration, the lower horizontal wall of the slot 46^c just underlying the striker arm 35 (see Fig. 6) preferably without engaging the arm 35 and thereby restricting the stress with which the spring 32 presses the contact 32^b into engagement with the contact 38, the upper horizontal

wall or edge of the slot 46^c becomes positioned at a height so that the upward strokes of the striker arm 35 are sufficient in length to interrupt the energizing circuit at the contacts 32^b and 38, but are shortened so that the striker 36 does not impact the rim of the gong 11. The vibration and whipping of the striker arm 35, with its length of stroke thus restricted, results, however, in the striker arm 35 repeatedly or in rapid succession striking against the upper and lower horizontal walls of the slot 46^c, emitting a buzzing noise from the resultant action and impacts of the parts. Fig. 6 shows the parts positioned for the just-described buzzer action, whereas in Figs. 2-5 the parts are shown positioned for bell-action; as better appears in Figs. 2 and 3, the lower edge of the side wall 11^a of the gong 11 is cut away, as at 11^c, throughout a short portion of the depending peripheral edge, forming in effect a recess or slot in the lower edge of the gong. This recess 11^c is so positioned in relation to the arcuate slot 28 in the gong 11 that, upon turning the gong to set the change-over device 46 for buzzer action, the recess 11^c is moved into position above the striker head 36 (see Fig. 6) to better make sure that as the striker 36 is whipped up and down during buzzer action, any springiness in the striker arm 35 or its mounting will not permit the striker 36 from actually striking the gong 11.

Whipping action is highly desirable for ringing the gong, and the elongated armature structure and its laterally displaced mounting, even though many of the structural parts are compacted to be accommodated underneath a very small gong, bring about excellent whipping action during vibration and in order to give such action freer play, the plate portion 10^a of the frame 10 (Fig. 6), in line with the elongated wide slot 10^b, is displaced at 10^e underneath and along the line of the striker 36 and its arm 35, thus giving the striker 36 more range of downward movement during vibration and thus enhancing the whipping action. The depressed portion 10^e (Figs. 3, 5, and 6) is preferably curved in the transverse cross-section, providing an upwardly concaved space (Figs. 3 and 6) into which the striker 36 may swing, and to cover over the slot 10^b (Figs. 5 and 6) so as not to downwardly expose the interrupter and armature parts, I provide two opposed pair of ears 49-49 and 50-50 (Fig. 5) which are struck downwardly (upwardly in Fig. 5) out of the frame plate 10^a at acute angles to the plane of the plate 10^a, and into the opposed pairs of angles is inserted a sheet 51 of insulating material such as hard fiber, the sheet being manually flexed or curved to get it into position, whence its tendency to straighten out maintains its opposed edges seated in the above-mentioned angles. Thus the sheet or cover 51 is detachably held in closing position and may be easily removed for access to parts thereunder.

Upon completion of assembly of the above-described parts, an annular sheet-metal and preferably ornamental frame ring 52 (Figs. 6, 4 and 1) completes the assembly, the ring 52 comprising a cylindrical side wall 52^a which telescopically interfits with the flange 12 of the base 10 and may be detachably interlocked therewith by providing the parts 52^a and 12 with suitable interfitting internal and external beads, as at 12^a and 52^b, so as to releasably spring or snap the parts together for holding them assembled or to spring them apart for disassembly. The frame ring 52 has an upper annular wall portion 52^c

which overlies the annular area A (see Figs. 2 and 3) of the base plate 10 and thus covers over the parts that are accommodated in that annular area A. The annular portion 52^c (Figs. 4 and 6) may be given any desired ornamental configuration, and it terminates with its inner periphery closely spaced about the gong side wall 11^a somewhat above the lower edge of the latter. As indicated in Fig. 1, the resultant structure would appear to comprise only the gong 11 and the frame ring 52 and their concentric relationship and their respective configurations with the structure in neat and compact appearance.

In the annular portion A of the frame plate 10^a I provide an aperture 10^k (Figs. 3 and 6) which underlies the right-hand end portion of the armature mounting, particularly the part 31^a which is bent out of the vertical frame part 31 of the frame 23, and in the part 31^a I provide a transverse slot 31^k dimensioned to receive therein a tool such as an average-sized screw-driver. Such a tool may be inserted from underneath into the slot 31^k by passing it through the aperture 10^k, or it may be inserted from above if the frame ring 52 is first removed. In either case, by using the screw-driver as a lever, the arm part 31^a may be bent to set it at such an angle to the frame part 31 as will in turn properly position the armature 22 and striker arm 35 in relation to the parts with which they respectively coact, particularly with respect to the slot 46^c in the change-over lever 46, so as to insure proper buzzer coaction between the walls of the slot 46^c and the striker arm 35 and to insure the desired bell action of the striker 36 upon the gong. Slot 31^k may thus be employed during assembly and testing, or even for adjustment of the device after installation. If necessary, the insulating cover plate 51 may be removed to gain access to the arm 39^a that carries one of the interrupter contacts, so that the arm 39^a may be adjusted by bending to obtain the desired interrupter action for the setting given to the armature and striker.

If the change-over device 46 is made of a magnetic material, it can take part in forming part of the magnetic circuit of the electro-magnet, the principal flux path comprising the core 21 (Fig. 6), the right-hand part of frame part 25, frame part 31, arm 21^a, and the armature 22; while another path comprises the core 21, frame part 24, change-over lever 46, striker arm 35, and armature 22. With the device 46 set for bell action as in Fig. 4, a substantial air gap is interposed between it and the striker arm 35, diminishing the effect of the second-mentioned flux circuit, and with the first flux circuit then essentially effective, the whipping action of the armature and striker structure is enhanced. When the device 46 is set for buzzer action, during which whipping action is less material, the lower hook-shaped portion of the lever 46 is brought into enveloping relation to the striker arm 35, the air gap is diminished, and the second above-mentioned flux path, with the air gap varying as the striker arm 35 vibrates between the upper and lower horizontal walls of the slot 46^c, can coact to increase the intensity of the impacts of the striker arm 35 against the walls of the slot and thus enhance the intensity of the buzzer action.

It will thus be seen that there has been provided in this invention a construction in which the various objects above mentioned, together with many thoroughly practical advantages, are successively achieved. It will be seen that the

construction is of a thoroughly practical character, is of efficient and reliable action, and is compact and ornamental in appearance.

As many possible embodiments may be made of the above invention and as many changes might be made in the embodiment above set forth, it is to be understood that all matter hereinbefore set forth, or shown in the accompanying drawing, is to be interpreted as illustrative and not in a limiting sense.

I claim:

1. In a signalling construction, in combination, a sheet-metal frame carrying an electro-magnet and having an arm-like extension that is bendable relative to the rest of the frame, said extension having secured thereto a flat spring element carrying an armature element for coaction with said electro-magnet, signalling means responsive to actuation of said armature, and means forming an enclosure for said electro-magnet and said arm-like extension, said frame extension having means engageable by a tool for bending it relative to the rest of the frame and thereby to fix the relationship between the armature element and said electro-magnet and said enclosure means having aperture means through which said tool may be introduced and engaged with said frame extension.

2. In a signalling construction, in combination, an electro-magnetic element and a coacting armature element, means forming a mounting and enclosure therefor, and signalling means responsive to actuation of said armature element, said armature element having means mounting it for movement relative to said electro-magnetic element including a bendable bracket-like part which, upon being bent, alters the coacting relationship between said two elements, said bracket-like part having a hole therein for the reception of a lever-like tool such as a screwdriver for bending said part, and said enclosure means having aperture means through which to pass the tool for insertion into said hole.

3. A signalling construction comprising means forming an enclosure and having therein an electro-magnet and an armature element for coac-

tion therewith with means for supporting said electro-magnet, said armature element being supported in operative relation to said electro-magnet by a bendable member which has a hole therein for the reception of a tool for bending said support member and thereby affect the coacting relationship between the armature element and the electro-magnet, said enclosure means providing a passageway for the entry of said tool into the hole in said bendable support member, and signalling means responsive to actuation of said armature element.

4. A signalling construction comprising an electro-magnet having an armature, signalling means responsive to actuation of said armature, support means for said electro-magnet, an armature-carrying element connected to said support means to position said armature in operative relation to said electro-magnet, the portion of said electro-magnet support means to which said armature-carrying element is connected being movable to adjust the position of said armature-carrying element and thereby change the position of said armature relative to said electro-magnet, said armature-carrying element having an aperture therein to receive a tool adapted to effect change of position of said armature-carrying element, and means forming an enclosure for said electro-magnet and said armature support means and said armature-carrying element, said enclosure means having aperture means in a wall thereof juxtaposed to said aperture in said electro-magnet support means for the passage therethrough of a tool adapted to be received in said aperture to adjust the position of said armature-carrying element.
